(57) **CLAIM**

The ornamental design for a mesh ball bag, as shown and described.

DESCRIPTION

FIG. 1 is a perspective view of a mesh ball bag showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, the handle being shown in an alternate position.

The broken lines shown in the figures are for the purpose of illustrating environment and form no part of the claimed design.

Portions of the claimed design are shown separated and bound by a bracket to indicate indeterminate length.

1 Claim, 5 Drawing Sheets
